UNITED STATES PATENT OFFICE.

FRED C. AREY, OF OAK PARK, ILLINOIS, ASSIGNOR TO HIMSELF; JOHN W. GLEASON, OF PITTSBURGH, PENNSYLVANIA; FRANK A. BORA, OF NEW YORK, N. Y.; WILLIAM F. FREUDENREICH, OF KENILWORTH, ILLINOIS; AND FREDERICK H. CHETLAIN, OF CHICAGO, ILLINOIS, TRUSTEES.

MACHINE FOR EXPANDING SHEET METAL.

Application filed May 18, 1925. Serial No. 30,900.

- There are various types of machines for expanding a slitted sheet to open up the strands and produce a mesh of more or less diamond shape, one of these types operating on the principle of pushing portions of a slitted sheet, underlying and moving past a row or series of stationary dies arranged in step formation over said dies and out of the plane of the sheet, so as progressively to expand the sheet from one side toward the other; and the object of the present invention is to simplify and improve the construction and operation of machines of this latter type.
- In machines of the type in question, as heretofore constructed, the slitted sheet enters the expander with its transverse lines horizontal, and travels up an incline; thus requiring the machine to be very high at the discharge end of the expander. One of the objects of the present invention is so to construct and arrange the parts of the machine that the machine as a whole is substantially horizontal, no portion thereof being necessarily any higher than the slitting mechanism or machine.
- In order to keep the machine low and horizontal, it is necessary that the slitted sheets be approximately vertical, rather than horizontal at the point of entry into the expanding mechanism; and, since the work is passed through the slitting rolls in a horizontal condition, it is necessary that the slitted sheet be twisted between the point of slitting and the point of entry into the expander. If one end of a horizontal metal sheet is grasped and is twisted until that end is vertical, it will be found that the metal does not set itself in gradual curves, but that it is natural for the sheet to attempt to crease itself and to buckle at opposite sides of the crease. One of the objects of the present invention is to produce a simple and novel means for effecting a twist in the slitted sheet, in such a manner that the sheet will not be subjected to uneven stresses, but will lay itself in such curves that there is no tendency for any longitudinal line to be lengthened or shortened.
- A further object of the present invention is to produce a novel construction and arrangement of dies and pushing wheels or discs.
- Due to the natural resiliency of the steel of which expanded metal lath is made, the strands tend to spring back more or less after they leave the expanding disc or wheel; and, viewed in one of its aspects, my invention has for its object to produce, a simple and novel construction and arrangement whereby the strands, upon leaving the expanding wheel, are held and guided so as to maintain them in the positions in the expanded sheet into which they were initially brought.
- The various features or novelty whereby my invention is characterized will herein-after be pointed out with particularity in the claims; but, for a full understanding of my invention and of its objects and advantages, reference may be had to the following detailed description taken in connection with the accompanying drawings, wherein:
- Figure 1 is a top plan view of a machine arranged in accordance with my invention; Fig. 2 is a side elevation of the machine; Fig. 3 is an elevation of a fragment of the slitted sheet, partially expanded; Fig. 4 is a side elevation on the plane represented by line 4-4 in Fig. 5, of a group of the stepped dies and feed rolls in front of which lies the sheet that is to be expanded, which sheet, at this point in the machine, has the appearance of that in Fig. 3; Fig. 5 is a transverse section, on an enlarged scale, through a portion of the expander, approximately on the irregular line 5-5 of Fig. 6; Fig. 6 is a section taken approximately on line 6-6 of Fig. 5; Fig. 7 is a view similar to Fig. 5, on a smaller scale, showing the entire machine, instead of only a fragment; Fig. 8 is a section through the guide, for twisting the sheet taken approximately on line 8-8 of Fig. 1, but, being on a larger scale than Fig. 1; Fig. 9 is a top plan view, partly in section a fragment of the expander, showing the adjustable supports for the feed rolls, namely a view taken approximately on the plane of the irregular line 9-9 in Fig. 10; Fig. 10 is a section taken approximately on the irregular line 10-10 of Fig. 9; Fig. 11 is a section taken approximately on line

11—11 of Fig. 7 and Fig. 12 is a section taken approximately on line 12—12 of Fig. 7.

Referring to Figs. 1 and 2 of the drawings, 1 represents a long solid horizontal base. On one end of the base is mounted a suitable rotary slitting machine 2 of any usual or suitable type. Near the opposite end of the base is arranged the expanding machine indicated as a whole at 3; the expanding machine lying at an acute angle to the longitudinal center of the base and to the axes of rotation of the slitting rolls. Between the slitter and the expander is a long warped table 4, somewhat wider than the slotted material delivered from the slitting machine. Overhanging guides, 5, 5 are fastened to the table along the side edges, for the purpose of loosely holding the work on the table. The table is twisted between its ends so that the end in the vicinity of the expander is vertical; the intermediate portion being in the form of a reversed curve such that any line running lengthwise of the table at a uniform distance from one of the long edges, is as long as any other line. Therefore when a sheet is fed along the table it naturally twists and bends itself to follow the contour of the latter.

Just in advance of the expander is a feeding device 6 having suitable rolls between which the sheet passes. The expander consists of two long frame members 7 and 8, best shown in Fig. 7, these frame members being U-shaped in cross section; the webs of these members being arranged parallel with each other and the flanges projecting in opposite directions. The member 8 is deeper than the other member and rises at the top above the plane of the top of the latter. Between the two frame members are two rows of vertical shafts 9 and 10. Each of the shafts 9 is geared at its lower end to the opposite shaft of the other group, by means of gear wheels 11, one on each of the two shafts; the gear wheels being of equal size so that the shafts will rotate at the same speed. The shafts 9 are driven in pairs, as best shown in Fig. 11, there being a gear wheel 13 meshing with each consecutive pair of gear wheels on the shafts 9. The gear wheels 13 are fixed to vertical shafts 14 each provided, between its ends, with a spiral gear 15; these spiral gears meshing with complementary gears 16 on a horizontal shaft 17 extending lengthwise of the expander underneath the lower flange of the frame member 7. Each of the shafts 9 has an enlargement 18 near its upper end, at about the top of the frame member 7. Each of the shafts of the other row has a similar enlargement 19 longer than the parts 18 and projecting upwardly above the upper ends of the members 18. The enlargements 18 and 19 are knurled or roughened so as to permit them to secure a tight grip on a slit-

ted sheet fed between them, such a sheet being shown at A in Fig. 5.

On top of the frame member 7 are fastened a number of blocks 20, each overhanging the space between the two frame members, and each supporting the upper ends of one of the shafts 9; each support being preferably in the form of a ball bearing 21. The inner vertical faces of the blocks extend close to the enlargements 19 on the shafts 10. Overlying the inner ends of the blocks 20 are a large number of comparatively small shoes or dies 22 that project into the plane of the vertical working faces of the blocks 20 and so disposed that, as viewed from the side, they present a step-like contour highest at the inlet end of the expander. These die members are simply laid in suitable seats 23 in the blocks and are held in place by means of a clamping plate 24 which may be in two or more sections. Upon removing the clamping plate, which is fastened to the blocks 20 by means of strong screws 25, the die members are left free and may be removed or replaced. The top of the inner end of the clamping plate 24 is inclined at an acute angle and has attached thereto, as a continuation of this inclined face, a table 26 on which the expanded work rests as will hereinafter be described.

Upon each of the shafts 10, above the enlargement 19 thereon, is a thick disc or wheel 27 extending across the tops of the dies 22 at their inner margins, and being spaced apart from the highest points on these dies a distance equal to the width of one of the strands, *a*, of the expanded metal. The lower side of the disc or wheel is cut away for a short radial distance along the periphery to form a secondary lower face 28 spaced apart from the tops of the dies a distance equal to the width of two of the strands of the expanded metal.

The upper end of each of the shaft 10 is supported in a suitable ball bearing 29 eccentrically mounted in a cylindrical block 30 rotatably mounted in a rigid supporting plate or beam 31 fastened on top of the frame members 8 and projecting therefrom across the upper ends of the shafts 10. Each of the blocks 30 has a stem 32 rising through the support 31 and having fixed thereto an arm 33, as best shown in Figs. 9 and 10. To the free end of each of the arms 33 is hinged a rod 34 passing loosely through an ear 35 on the support 31. On the free end of each rod, beyond the corresponding ear, is a strong coiled spring 36 resting against a thumb nut 37 screwed on the extreme end of the rod. These springs are under an initial tension and tend constantly to turn the bearing blocks 30 in a direction to force the shafts 10 toward the shafts 9. In other words, a sheet that is passing through the machine is being yieldingly pressed against

the stationary blocks 20 and the enlargements 18 on the rolls 9, by the enlargements 19 on the other rolls. The slotted sheet to be expanded is fed between the feed rolls as the 5 enlargements 18 and 19 may be called, with a marginal portion projecting outwardly beyond the dies 22 far enough to overlap the outer rim of the first wheel 27. As the sheet is fed forward, this marginal edge engages 10 with the periphery of this expanding wheel and is pushed laterally across the top of the dies. It is the outermost or marginal strand that is engaged by the first wheel and, in pushing this strand outwardly, it also draws 15 on the second strand from the edge, as well as the third strand; the second strand being guided into the annular notch 28 in the wheel, the third strand lying between the under face of the wheel and the top of the 20 die, and the fourth strand being still engaged with the vertical face of the die. As the work advances, the upper faces of the dies recede, in step formation, from the horizontal plane of the first of the spreader 25 wheels, and therefore the spreader wheels as well as the feeding roll members 18 and 19 are arranged in step formation, the second set being lower than the first and the third set lower than the second, and so on to the 30 end of the series; Figs. 4 and 10 showing their step formation. The members 31 in which are mounted the bearings for the upper ends of the shafts 10 are therefore made in sections corresponding in number to these 35 shafts; thus permitting the step formation of the supports for the upper ends of the shafts 10 to be readily obtained.

By the time the work reaches the second spreading or expanding wheel, it is the fifth 40 strand from the outer edge that rides up over the periphery; while the ninth strand engages a third wheel. In other words, there are one-fourth as many wheels as there are strands across the sheet. Fig. 5 is typical of the condition that exists at each wheel, one of the strands riding the periphery of the wheel and drawing out the next strand through the connecting bond *b*; the second and third strands lying between the under 45 faces of the wheel and the top of the corresponding die, and the fourth strand, which still lies in the plane of the unexpanded portion of the sheet, lying against the vertical face of the die. It will be seen that one-half 50 of the bond *c* between the third and fourth strands is engaged with the vertical face of the die, while the other half extends across the gap between the top of the die and the under face of the expanding wheel against 55 which it abuts. Consequently this latter bond prevents the fourth strand from being pulled out vertically past the die.

As the sheet is expanded, the expanded portion wells out upon the table 26 and 60 moves lengthwise of the table. There is a

tendency for the strands to spring back more nearly into straight lines, after the initial expanding operation; and, to prevent this, I have arranged above the table 26 a long 70 guide bar 40 having in the face directed toward the table a series, of long ridges 41 between which the expanded strands feed and by which these strands are held guided so that the finished sheet will have straight parallel sides. In the arrangement shown, 75 as will best be seen from Figs. 1 and 7, the toothed bar 40 is carried on the end of two arms 42 extending transversely of the table 26 and projecting beyond the same at the edge farthest from the working faces of the 80 dies. Each arm is hinged at its outer end to a bracket 43 fixed to the table. There is a rod 44 hinged to each bracket and extending loosely through the corresponding arm 42. On the outer end of each of these rods is an 85 adjustable nut 45, and between the nut and the arm 42 is a spring 46. This arrangement, it will be seen, serves yieldingly to hold the toothed guide 40 upon the work.

There are more or less fine metal particles 90 that drop from the work as it is being expanded and, in order to prevent these particles from entering the bearings for the lower ends of the shafts 9 and 10, I place between the two frame members 7 and 8 a 95 two-piece baffle plate or platform, one member, 50, of which is fixed to the frame member 7 while the other member or section, 51, is fixed to the frame 8. The shafts 9 extend through the member 50 and fit the holes 100 through which they pass; the same being true of the shaft 10 and the member 51. Each of the members 50 and 51 contains a layer 52 of packing material, that insures dirtproof joints between these members and the shaft. The edge of the member 50 that engages with the member 51, is in the form of a trough 53 that receives the edge of the member 51.

The lower ends of the shafts 9 are mounted 110 in suitable bearings fixed in relation to the frame member 7, while the lower ends of the shafts 10 have bearings that are fixed in relation to the frame member 9. Therefore, the machine may be opened by moving 115 the frame member 8 laterally, carrying the shafts 10 and the feed rolls 19 thereon away from the cooperating shafts and feed rolls. During such separating movements, the sections 50 and 51 of the baffle plate or waste 120 catcher also move away from each other, but retain on their upper surfaces such foreign matter as may have collected thereon.

At the end of the table 26 is a mechanism 60, of any usual or suitable type, through 125 which the expanded product passes and by which it is rolled so as to insure that it will be in the form of flat unwarped sheets.

It will thus be seen that I have produced a simple and novel machine for making ex- 130

panded metal lath or the like, in which a slitted sheet is progressively drawn over a stepped arrangement of dies to open the strands; the work being so disposed and so manipulated that the machine as a whole is low and the work is at all times under the observation of a person standing on the floor beside and looking down at the machine. It will also be seen that I have provided a simple expanding arrangement that does away with the need for rolls or dies to produce an initial partial opening of the strands; and, further, that I have provided a simple means for twisting the slitted sheet from a horizontal to a vertical position, without danger of distorting the sheet or of introducing objectionable stresses therein; and finally that I have provided a simple means for holding the expanded strands against their tendency to spring back, and guiding the finished product so as to insure substantial parallelism of groups of strands from one edge of the expanded sheet to another.

25 While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In a machine of the character described, a slitting mechanism adapted to act on a horizontal sheet, an expanding mechanism adapted to expand a slitted sheet entering the same in a vertical position, and means between said mechanisms for guiding a slitted sheet in such a path that all points in the sheet move through curved paths of equal lengths.
2. In a machine of the character described, a slitting mechanism adapted to act on a horizontal sheet, an expanding mechanism adapted to expand a slitted sheet entering the same in a vertical position, and guides between said mechanisms adapted to cause the sheet to be bent so that one end is vertical while the other remains horizontal.
3. In a machine of the character described, a slitting machine adapted to act on a horizontal sheet, an expanding mechanism adapted to expand a slitted sheet entering it in a vertical position, and a guiding table between said mechanisms; one end of the table being horizontal, the other end being vertical, and the intermediate portion being bent on a reverse curve.
4. In a machine of the character described, a row of stepped dies, expanding wheels arranged beside the dies, each wheel having its central portion spaced apart from the nearest dies a distance substantially equal to the width of a single strand of the metal

to be expanded and the peripheral portion spaced apart from such die a distance substantially equal to the width of two strands.

5. In a metal expanding machine, a row of dies arranged in step formation with their end faces in the same plane, a series of expanding wheels rotatable about axes parallel to said plane, each wheel overlapping the dies and having a central portion spaced apart from one of the dies a distance approximately equal to the width of one of the strands of the sheet to be expanded and having a peripheral portion spaced apart from the latter die a distance approximately equal to the width of two of such strands, and means for feeding a slitted sheet past and in contact with said end faces with the bonds in certain rows in the slitted sheet engaged with said end faces and projecting across the gaps between the centers of said wheels and the dies nearest thereto and contacting with the centers of the wheels to prevent bodily transverse displacement of the sheet.

6. In a metal expanding machine, a row of dies arranged in step formation with their end faces in the same plane, a series of expanding wheels rotatable about axes parallel to said end faces and overlapping said dies, and means for feeding a slitted sheet past and lying flat against said end faces, the parts being so proportioned that the wheels engage peripherally with longitudinal rows of bonds spaced at regular intervals apart across the sheet while another row of bonds near each of the aforesaid rows lies partially against said end faces of the dies and projects beyond the dies into contact with the side of the corresponding wheel.

7. In a metal expanding machine, a support, a series of narrow die blocks lying side by side on said support and having their end faces at one end lying in approximately the same plane, a plate overlying said die blocks and projecting beyond the blocks at their other end, and means for fastening said plate to said support to clamp the die blocks in place.

8. In a metal expanding machine, a support, a series of narrow die blocks resting side by side along a marginal portion of said support and having their working faces in the vicinity of the edge of said marginal portion, a clamping plate extending across said blocks and resting at one edge on the blocks and at the other edge on said support, and adjustable fastening means passing through said plate and into the support to draw the plate and support into clamping relation with respect to the die blocks.

9. In a machine of the character described, a frame, a vertical shaft at one side of the frame, a stationary bearing on the frame for the lower end of said shaft, a feed roll on

the shaft, an expanding wheel on the shaft above the feed roll, and an adjustable bearing on the frame for the upper end of said shaft.

- 5 10. In a machine of the character described, two long frames arranged side by side and spaced apart from each other, a row of vertical shafts mounted in stationary bearings on the side of the first frame facing the second frame, a corresponding row of vertical shafts mounted on the second frame opposite the other shafts, the bearings for the lower ends of the second row of shafts being stationary and the bearings for their upper ends being yieldingly pressed toward the opposite shafts, feed rolls on said shafts, dies on the top of the first frame, and expanding wheels fixed to the shafts on the second frame in position to overlie the dies.
- 10 15. In a machine of the character described, a table, means for feeding a slitted sheet along one edge of the table and expanding it so as progressively to spread it on the table, and guide elements overlying the table and extending lengthwise thereof at an acute angle to the aforesaid edge, said guide elements being spaced at such a distance above the table that they will engage the strands of the expanded sheet and compel them to travel along the said guide elements.
- 20 25. In a machine of the character described, a row of staggered dies, a table beside said dies, means for moving a slitted sheet along said row of dies progressively to expand the same into open mesh and deliver it to said table, and guide elements overlying the table and extending lengthwise thereof in the direction of travel of the sheet along the table, said guide elements being spaced at such a distance apart and at such a distance above the table that
- 30 35. In a machine of the character described, two long frames arranged side by side and spaced apart from each other, a row of vertical shafts mounted on the side of the first frame facing the second frame, a corresponding row of vertical shafts mounted on the second frame opposite the other shafts, the mountings of said shafts being such as to permit yielding movements of the shafts of one row away from the shafts of the other row, feed rolls on said shafts, dies on top of the first frame, and expanding wheels fixed to the shafts on the second frame in position to overlie the dies.

they will engage the strands of the expanded sheet and compel them to travel along said guide elements.

45

13. In a machine of the character described, two long frames arranged side by side and spaced apart from each other, a row of vertical shafts mounted on the side of the first frame facing the second frame, a corresponding row of vertical shafts mounted on the second frame opposite the other shafts, the mountings of said shafts being such as to permit yielding movements of the shafts of one row away from the shafts of the other row, feed rolls on said shafts, dies on top of the first frame, and expanding wheels fixed to the shafts on the second frame in position to overlie the dies.

50

14. In a machine of the character described, a frame, a die at the top of the frame, a vertical shaft below said die, a second vertical shaft arranged beside the said first shaft, feed rolls on said shafts, an expanding wheel on the upper end of the second shaft in operative relation to said die, and means for supporting said shafts so as to permit yieldable relative movements from and toward each other.

60

15. In a machine of the character described, a slitting mechanism adapted to act on a horizontal sheet and an expanding mechanism adapted to act on a slitted sheet entering the same in a vertical position to expand the same and cause the expanded portions to lie at a considerable angle to the vertical, and means between said mechanisms for guiding a slitted sheet so as gradually to bring it from a horizontal to a vertical position.

70

In testimony whereof, I sign this specification.

75

FRED C. AREY.
